UNITED STATES PATENT OFFICE.

CLARENCE W. MABLE, OF BINGHAMTON, NEW YORK.

METHOD OF COLORING MOVING-PICTURE FILMS.

1,230,744.

Specification of Letters Patent. Patented June 19, 1917.

Application filed April 28, 1916. Serial No. 94,228.

To all whom it may concern:

Be it known that I, CLARENCE W. MABLE, a citizen of the United States, and a resident of Binghamton, in the county of 5 Broome and State of New York, have invented a new and Improved Method for Coloring Moving-Picture Films, of which the following is a full, clear, and exact description.

10 Among the principal objects which the present invention has in view are: To provide moving-picture films with uniform color tints evenly applied; to blend the tones of the material employed in coloring 15 the films; and to reduce the time and labor required for coloring said films.

Drawings.

Figure 1 is a representation of a photographic film employed in moving-picture projecting machines, showing a view photographically printed thereon in the usual manner;

Fig. 2 is a view of a fragment of color-transfer ribbon employed in tinting the film;

Fig. 3 is a view similar to Fig. 2, showing the same as having been tinted in accordance with the present method, employing therein the ribbon shown in Fig. 2;

Fig. 4 is a cross section on an enlarged scale, of the ribbon shown in Fig. 2, the section being taken as on the line 4—4 in Fig. 2;

Fig. 5 is a side elevation of a tinting machine employed in carrying into effect the present method.

Description.

40 When tinting photographic films 10 of the character mentioned, in accordance with the present invention, the film such as shown in Fig. 1, is overlaid by a clear transfer ribbon 11. The ribbon 11 is preferably 45 formed of similar material to that employed in producing the film 10, and usually is a spoiled or imperfect film which has been cleared of its photographic prints if such have been imparted thereto.

50 If several colors are to be used in coloring the films, the ribbon 11 is usually marked or blocked off as a master plate for the blocking of other ribbons to be used in series. As shown in Fig. 2 of the drawings, 55 the ribbon 11 has been blocked for print-

ing or tinting the spaces indicated on the film 10, by the numerals 12, 13, 14 and 15.

The blocking above referred to is formed on each of the ribbons 11 employed in producing the poly-colored films, which result 50 from the employment of the present method. This blocking consists in painting or coating the ribbon 11 with any suitable chemical, such as bichromate of potassium, except where the tinted spaces are to remain. Referring to Fig. 2 of the drawings, the ribbon 11 is therein shown as having been coated with bichromate of potassium, except where the spaces indicated by the numerals 12 to 15, inclusive, are shown. 55

After being thus treated, the ribbon 11 is permitted to dry. It is then immersed in water for an ascertained period of time sufficient to permit the water to affect the parts of the ribbon unprotected by the bichromate of potassium, to swell the gelatin with which the ribbon is preferably coated. It will be obvious from what hereinafter follows, that although the swelling of the portions, such as indicated by the numerals 60 12 to 15, inclusive, is preferred, this is not essential to the carrying into effect of the present method of tinting.

After the exposed sections have been sufficiently acted upon by the water to raise 65 the surface of the indicated sections above the ordinary surface of the ribbon, the latter is prepared for use as a tint-transferring medium.

It will be understood that if a series of 70 colors are to be used, each color will be provided with a separate ribbon 11, the blockings or exposed and swelled sections thereof having been located in accordance with a master ribbon indicating the areas for the 75 special color to be transferred by the particular ribbon. It is obvious that as in the usual methods of photolithography, the tints may be varied by overlaying or superimposing a color or colors, the colors employed being preferably transparent colors. In tinting films of the character herein mentioned, the usual anilin colors are employed.

Having prepared the series of transfer 100 ribbons necessary to tint the film 10, the ribbons are placed on a reel 16, supported in the arms 17 of a printing machine, such as shown in Fig. 5. The ribbon 11 is passed under an immersing roll 18, where it is sul 110

- merged in coloring or tinting liquid held in a fountain 19. From the fountain 19, the ribbon 11 passes over a wiping roller 20, and under a guide roll 21. From the guide 5 roll 21, the ribbon 11 is carried between pressure rolls 22 and 23, the latter of which has a series of pins 24 for engaging the perforations 25 of both the film 10 and ribbon 11. The film 10 is held on a reel 26 10 in the printing machine to be drawn therefrom by the roll 23, to pass between the rolls 22 and 23 into contact with the ribbon 11 and with the swelled and tint-transfer areas 12 and 15, inclusive.
- 15 When the ribbon 11 passes over the roller 20, all surplus color is removed therefrom, so that the ribbon 11 after passing the said roller, carries the color from the fountain 19, on the sections 12 to 15, inclusive, only.
- 20 Therefore, when the ribbon 11 and film 10 are pressed together on passing the rolls 22 and 23, the color carried by the said areas 12 to 15, inclusive, on the ribbon 11, is transferred to the film 10 and to the areas indicated by the numerals 12 to 15, inclusive, 25 in Fig. 1 of the drawings.

When the tint thus imparted to the film is dried, the film is again treated in the same manner by other ribbons 11 having other tint-carrying transfer areas.

It will be understood that having started the film 10 correctly registered with the ribbon 11, the pins 24 insure thereafter the accurate register of said film and ribbon throughout the printing or transfer of each single tint.

It is obvious that when following the herein-described method of tinting, the minor or smaller details of shades or "modeling" are provided by the photographic print or the relatively black tone of the photographic positive.

After the film has been completely tinted, it is dried ready to be exposed by the projectoscope or projecting machine onto the view screen. It will then be found that the various objects thrown on the screen, have the colors imparted to them. It will also be noted that the tints are evenly transferred 45 throughout the length of the film 10, owing to the even rate of speed of said ribbon and film to the pressure rolls 22 and 23. This, when contrasted with the hand method employed for coloring photographic films, 50 shows an appreciable difference in favor of the mechanically tinted film resulting from

the employment of the herein-disclosed method.

While the material used for projecting the film from the action of water has been 60 mentioned herein as bichromate of potassium, it will be understood that any other suitable solution may be used, such as any of the chromium salts.

Claims.

65

1. A method for coloring a photographic film consisting in providing a transfer ribbon corresponding in size with said film; then rendering said ribbon impervious to 70 an aqueous solution, omitting printing areas to be treated by said solution, said areas registering with associate areas on said film; then immersing said ribbon in an aqueous solution to affect said areas; then passing 75 said ribbon through a printing solution; then pressing said film and ribbon together in registered relation for transferring the printing solution held by said printing areas of said ribbon to the associate areas of said 80 film.

2. A method of coloring a photographic film consisting in providing a transfer ribbon corresponding in size with said film; then locating printing areas on said ribbon, 85 said areas registering with associate areas on said film; then rendering the surface intermediate said areas impervious to the action of aqueous solutions; then immersing the ribbon in water for acting on said printing areas; then immersing said ribbon in color solution; and then pressing said ribbon and said film together for transferring the color solution from said printing areas to said associate areas.

3. A method of coloring a photographic film consisting in providing a transfer ribbon corresponding in size with said film; then locating printing areas on said ribbon, said areas registering with associate 100 areas on said film; then rendering the surface intermediate said areas impervious to the action of aqueous solutions; then immersing the ribbon in water for acting on said printing areas; then immersing said 105 ribbon in color solution; and then pressing said ribbon and said film together for transferring the color solution from said printing areas to said associate areas, said ribbon and film being held in registry while 110 pressure is being applied thereto.
